UNITED STATES PATENT OFFICE.

JEREMIAH GREENWOOD, OF FITCHBURG, MASSACHUSETTS.

IMPROVEMENT IN MACHINES FOR FORGING THE HEADS OF BOLTS.

Specification forming part of Letters Patent No. 123,822, dated February 20, 1872.

To all whom it may concern:

Be it known that I, JEREMIAH GREENWOOD, of Fitchburg, in the county of Worcester and State of Massachusetts, have invented certain new and useful Improvements in Machines for Forging Heads upon Bolts; and I do hereby declare that the following, taken in connection with the drawing which accompanies and forms part of this specification, is a description of my invention sufficient to enable those skilled in the art to practice it.

My invention is designed to produce upon heated round iron heads of any polygonal form, usually, however, hexagonal, and may be applied to any vertically-reciprocating hammer. In my invention the heated iron is sustained in a rotating carrier, above which it projects sufficiently, so that the head can be formed by upsetting the material so projecting, the upsetting being performed by blows from a die carried by any suitable reciprocator, and the material so upset being shaped to polygonal form by squeezers made to operate after each blow of the die, by the upward movement of the reciprocator, each upsetting blow preceding the action of the squeezers, which give, in connection with the degree of each partial rotation, the polygonal character of the head.

In the drawing, Figure 1 shows a vertical section of the parts involved in my invention and an elevation of what may be taken to represent a vertical hammer operated by steam or compressed air. Fig. 2 shows a side elevation of the same; Fig. 3, a sectional plan, the section being taken in the plane of the dotted line seen in Fig. 1; and Fig. 4 is a reversed sectional plan, showing the devices by which the carrier of the heated round iron is rotated.

a is supposed to represent the moving vertical cylinder of a Hotchkiss air-spring forging-hammer in common use; *b*, the part of the piston-rod outside of the cylinder to which the hammer-die *c* is connected, the spring *d* representing the elastic cushion afforded by air caught and confined between the piston and the cylinder-heads. In the lower part of the frame-work *e* of the forge-hammer is confined, in place of the ordinary anvil, a casting, *f*, with which the parts embodying my invention are connected. Concentric with the axial line of

the upsetting die *c*, and in the casting *f*, there is made a cylindrical recess, which receives carriers *g*, made with central holes bored to suit any diameter of round iron. These carriers are made to receive the ratchets *h* and *i*, by which the rotations of said carriers are effected and controlled, the lower end of each carrier fitting in a bearing in the ear *j*. In the bore of each carrier pins *k*, of any length, may be inserted to determine the length of each bolt under the head. The end of each gauge-pin *k* rests on lever *l*, the end of the short arm of which rests on the casting *e*. By depressing the long arm of said lever the bolt occupying the bore of the carrier is raised out or thrown out therefrom. On opposite sides of the carrier are slides *m m*, made so that they can reciprocate in suitable ways fixed to the casting *f*, said slides serving as ways for the slides *n n*, which act as the dies by which the polygonal faces of the heads of the bolts are formed. To slides *m m* the levers *o o* are pivoted, the short arms thereof bearing against slides *n n* and the long arms being brought into the path of the piece *p* attached to the reciprocating piece *b*. Said piece *p*, being angular at its top, opens or spreads levers *o o* as the piston and rod *a b* makes its upward stroke and causes the slides *n n* to move toward the center of carrier *g*, and to squeeze to shape any material that may be presented between the operative faces of said slides. Between cheeks *q* of casting *f* and slides *m m* are inserted inclines or wedges *r r*, the outer ends of slides *m m* having bevels or inclines corresponding to those of the wedges, which are caused to advance or to withdraw equally by the action on pins in the wedges of rocker-arms *s s*, which are slotted and which are fixed to rocker-shaft *t*, which is worked by hand by the lever *u*. The retractile movements of slides *m m* and the short arms of levers *o o* are effected by the spring *v*, which acts directly on pins inserted in slides *n n*. The slide *w* is reciprocated by attachment to the moving cylinder *a*, and by means of an inclined slot in *w* effects reciprocations of a bar, *x*, which has pivoted to it a pawl, *y*, which works the ratchet *i*, a detaining-pawl, *z*, operative on the same ratchet, preventing any reverse rotation while the pawl *y* fleets. To prevent motion in the direction given by the pawl *y* during the ac-

tion of the squeezing-dies h , the sliding-rod x is made to carry a pin, a' , which is brought under a tooth of ratchet h before the dies $n n$ operate, so that it will be seen that the carrier is held immovable during the movement of dies $n n$ while operating to form two opposite sides of a polygonal head.

In commencing to form a bolt-head, the wedges $r r$ are pushed fully in, and as material is brought down by the action of the die c for dies $n n$ to operate upon the wedges are drawn out by the attendant, so that dies $n n$ cease their inward strokes at points more and more remote from the center of the bolt, the size or diameter of the bolt-head being determined by the distance to which the wedges $r r$ are drawn outward. The height or length of the bolt-head is determined by the relation of the operative face of die c to the stop limiting the stroke of the hammer. Usually I cut screw-threads on the shank of the die c , and screw it into the reciprocating piece p , holding it immovable by use of a check-nut. The head of the bolt-carrier or holder g is located in a cylindrical recess of greater diameter, so that there is an annular space around the holder-head. In said head is a wing, b' , which in its rotations serves to wipe all of the scales falling from the heated iron through holes made through the casting in the bottom of said annular space. The operative parts of the machine subject to the heat of the iron are kept cool in action by the flow upon them of a small stream of water. The iron being cut off to the proper length and the carrier g being suited to its diameter and the pin k to the length of the bolt under the head, the iron is heated nearly or quite to a welding heat and placed in the holder; then, on reciprocation, the die c strikes the head of the hot iron and upsets it or drives it down and the dies $n n$ approach

and give form to the metal so displaced; the holder g then makes one-sixth of a rotation; the die c descends and more metal is upset, which the dies $n n$ shape, the dies $n n$ receding from the center as the operator draws out the wedges $r r$; and the operation thus proceeds until the head is fully formed upon the shank of the bolt.

To change the shape of the heads formed by the machine, it will be necessary to change the ratchets $h i$ and the slide w so as to have more or less teeth on the former and a different inclined groove in the latter. Ordinarily, however, there need be no departure from devices adapted to produce hexagonal heads.

The operation of forging bolt-heads by the means described, though gradual, is very quickly performed, leaving the fiber of the metal in the best condition, and producing a fine sound head without flaws, fully equal to, if not exceeding, the degree of excellence attained by hand-forging.

I claim—

1. The recessed bed, provided with escape outlets, the winged carrier rotating therein, and mechanism for rotating the same, combined and arranged to operate substantially as described.

2. Also, the combination, with the carrier g , of the oppositely - arranged equal - toothed ratchets $h i$, the bar x , the pawl y , and the detaining-pin a' , as and for the purpose specified.

3. Also, the combination with the slides $m n$, levers $o o$, and reciprocating wedge p and spring v , of the inclines r , arranged to be simultaneously and equally moved by the operator, as set forth.

JEREMIAH GREENWOOD.
